WORK SUPPORT

Lora Allen Mitchell, Birmingham, Ala.

Application June 14, 1943, Serial No. 490,828

6 Claims. (Cl. 1—13.5)

This invention relates to improvements in work supports, and has particular relation to structures utilized as supporting means for material during the fashioning of an assemblage which, in the absence of such means would be made more or less difficult; in explanation of the general characteristics of the invention, a brief description is given of the assembly that is to be fashioned by the use of the present invention.

In U. S. Design Patent No. 132,104, to Morton, there is disclosed the design of a Doll cradle, an assembly that is designed to provide a bassinet for a child's doll. In appearance, it is elaborate and ornate, appearing to be formed mainly of a frame with material properly draped thereover, to provide the effect of a cradle with a canopied effect. Structurally, the foundation of the cradle is a handleless basket of the type generally termed a "chip basket," to which is applied a handle—to produce a canopy base—and a supporting frame, with the structure generally hidden by the draped material which finally completes the assembly and which gives it its rich and ornate appearance.

Obviously, to construct the assembly from the material of which it is formed, much hand labor is essential, with much of this labor required in properly securing and draping the flexible material; without the use of a particular type of supporting means or work support, an acceptable assembly—especially one to be duplicated for marketing purposes—would be extremely difficult, due to the fact that the assembly must be fashioned about the "chip basket," the latter being an open-top basket formed in part of thin wood splints, etc., of low cost in production, being often used as a container for the marketing of fruits, etc.; the basket is therefore more or less of a shell, and the difficulties of attempting to build up the cradle assembly thereon without the use of a work support, can be understood. The basket actually forms the bed portion for the doll, and its shell-like form—open topped—offers no aid to the workman during the production; actually, it tends to hamper the development due to the difficulty of manipulating it into position for securing efficient draping effects.

The present invention was developed with a view to providing a work support which would maintain the shape, etc., of the somewhat fragile basket, and yet permit of its movement into the necessary positions needed to secure the best development results. In effect, the basket serves

as a shaping form which remains as a part of the finished product, but the work support used to permit the development to proceed with efficiency, serves to maintain the shape of the basket during the needed operations thereon, but is removable from the finished product, to permit the development of a succeeding cradle with a reasonable assurance of a general similarity between successive products.

10 In shape, the basket is of the elongated type at its open top—with rounded ends—and formed with a reinforced margin, the body being formed of the splints which may be braided or otherwise arranged, with a depth of possibly six inches, 15 the entire formation being of low cost of production; it is sufficiently sturdy for its service—in its normal field as well as in this special field—but in appearance it is neither ornamental nor ornate, and to change it to the highly ornate cradle formation by the development treatment of an ordinary work-a-day basket, requires manipulation as to positions of the basket for permitting draping activities at particular points and in particular ways, thus requiring not only the use 20 of a work support, but a support having a number of characteristic features.

For instance, the bassinet appearance requires the need of a semi-canopy effect, thus requiring the use of the equivalent of a basket-handle; but 30 it cannot well be standard handles of baskets of this type, since the position and angularity of such normal handles will not produce the desired effect; as a result, a special member must be secured as a substitute, and this must not only be properly located and shaped, but must be secured to the basket body—as by riveting or with clinched nails—and this must be done without danger of damaging the basket itself. Again, 35 draping and securing of material as the cradle develops, requires adjustment of the basket to different angles in order to permit the most efficient draping action; this must be made possible through the form of the support, since the basket alone would be more or less unmanageable 40 in these respects.

In other words, the work support must give to the developing structure the strength and maneuverability that is absent from the basket itself, and must do this in such way as to preserve the shape and integrity of the basket material, and yet permit removal of the completed structure from the support, to permit the beginning of the operations on the succeeding product, 45 by positioning a new basket.

The present invention, developed for the purpose, combines a number of elements so arranged cooperatively, as to permit these results to be obtained; in addition, it compensates for the inherent variations in dimensions which are found in a series of baskets of this type which provide only approximate similarity under the conditions of low cost of manufacture. As a result, the bassinet or cradle which forms the completed article, can be produced under reasonably low cost conditions, and with an assurance of substantial uniformity in product.

To these and other ends, therefore, the nature of which will be more clearly understood as the invention is hereinafter disclosed, said invention consists in the improved construction and combination of parts hereinafter more fully described, illustrated in the accompanying drawings, and more particularly pointed out in the appended claims.

In the accompanying drawings:

Figure 1 is a view in side elevation and partly in section, of a work-support according to the present invention, a basket to be draped being shown by dotted lines.

Figure 2 is a front elevation of the same, with the basket shown by dotted lines.

Figure 3 is a sectional view taken on line 3—3 of Figure 1.

Figure 4 is a bottom plan view of the same, with parts broken away.

Figure 5 is a sectional view taken on line 5—5 of Figure 3.

Figure 6 is a fragmentary side elevation of a modified form.

The work support is, in effect, an assembly supported on an arm 10—shown as extending horizontally, with the arm secured to a table top 11; obviously, this is illustrative of a simple and convenient way in which the assembly may be mounted, the underlying characteristic being that the mounting should be so arranged as to permit the assembly to swing about a horizontal pivot 12 from which the assembly is suspended and be capable of swinging in either direction about the pivot. In the form shown, the arm extends beyond the table top and is formed with a bifurcated end 10a into the slot of which extends the upper end of a vertical standard 13 of the assembly, pivot 12 extending through the latter to provide the axis for the swinging movements of the assembly, standard 13 having its upper end properly shaped to have its swinging movements within the slit of the bifurcated end 10a.

Standard 13 extends vertically and is of suitable length to place the assembly in a convenient position and height for the activities of the workman, and is formed with a lower end zone 13a of circular contour designed to permit of swinging movements of assembly parts on a vertical axis, as presently explained. As a result, the assembly is so mounted as to permit swinging of the assemblage into practically all positions needed for proper action by the workman. The supporting characteristic of standard 13 is provided by an end member 13b secured to the lower end of the circular zone, and of materially larger diameter than that of the circular zone.

Mounted on the circular zone is an upper member 14 designed to be positioned within the basket at the top or reinforced portion of the latter; hence, member 14 has a contour which approximates the internal contour of the basket top zone, although varied somewhat from an actual

fit. For instance, since it is essential that ready positioning of the basket can be had, member 14 is divided longitudinally into two parts—preferably of unequal width, the portion of lesser width—14a—being provided with dowel pins 15 designed to extend into suitable openings 16 of the other member, thus permitting the members 14 and 14a to be separated but be maintained in their normal planar relationship.

In addition, member 14 carries an underlying portion 17, a portion of which—17a—extends onto portion 14a, portions 17 and 17a extending into the basket below the top zone, and serving not only to reinforce member 14 but to provide a weight factor which normally tends to retain the assembly in its vertical position. The members 14 and 14a are subjected to tension by a spring 18 secured to portions 17 and 17a, and which tends to hold the members in their contacting positions.

Since the overall width of members 14 and 14a is less than the internal width of the basket, they can be readily positioned within the upper zone of the basket. To permit the members to be expanded, a camming member 19 is provided, this member having a camming portion 19a located in the zone of portion 17, and having a stem 19b extending upwardly to a point above member 14 and provided with a handle 19c, stem 19b having its axis aligned with the division line between members 14 and 14a. Obviously, when the basket has been positioned relative to members 14 and 14a, swinging of handle 19c will cause the two members to be separated by the action of the camming member 19a, thus bringing the outer sides of members 14 and 14a into contact with the interior of the sides of the basket top zone and thus retain the basket firmly in position on the assembly.

Since these baskets may differ slightly in dimensions, and with a view to aiding in properly positioning the basket, it is also preferred to add an adjustable member 20 at one end of member 14, this member being provided with dowel pins 20a designed to extend into slots 20b of member 14, suitable set screws 21 being provided to secure member 20 in adjusted position. Member 20 will thus act to maintain the basket against shifting longitudinally on the assembly.

As heretofore pointed out, the cradle or bassinet includes a canopy portion which is provided by initially fashioning a handle for the basket. The front of the canopy is generally varied from that of a perpendicular to the plane of the top of the basket, so that the commercial basket handle is less desirable—the reason for the use of baskets without handles. To provide the support for the canopy therefore requires the addition of a handle to the basket, and to secure the proper shaping of it, the member 14 carries a template 22 of proper shape over which the splint to be used as the handle can be properly shaped, the ends of the splint being carried downward through the reinforcing zone of the basket, where the ends are secured by clinched nails or rivets, members 14 and 14a carrying metallic surfaces 23 at proper positions to enable the workman to readily secure the handle in proper position by rivets or nails while the basket is in position on the assembly. After being secured, the excess ends of the handle are snipped off.

The canopy generally has its greatest projection at the top, so that the template 22 generally extends at an angle such, for instance, as is shown in Figure 3. However, it is apparent that

it may be desirable to reverse the canopy to increase the side effect; in such case, the angularity of the template is changed, as shown, for instance, in Figure 6, in which the angularity is opposite that shown by the template in Figure 1. While it would be possible, of course, to extend the template in actual vertical position—normal to the top plane of member 14—and such arrangement is considered to be within the purview of the invention, the appearance of the drapery is not as attractive under such conditions, and it is therefore preferred that the template be mounted to extend angularly to and normal to the top plane of the member, thus being angular to both the vertical and the horizontal.

As is apparent, with arm 10 positioned on the top of a table, the standard 13 and member 14 will be practically suspended therefrom at a convenient height for the workman. The handleless basket form is then positioned relative to member 14 with the latter in the zone of the open top of the form, with the basket-form practically anchored to the member by manipulating lever 19c to meet the conditions at the sides of the form and member 20 for the lengthwise direction. The canopy base form—the equivalent of a basket handle—is then draped over the template and secured to the basket by rivets or the like. This prepares the form for the draping activities by the workman. Since standard 13 can be swung on its horizontal pivot, carrying the positioned form with it, and member 14 is itself pivotally mounted on the standard, it is apparent that all parts of the basket form can be brought to a convenient position for the workman to perform his draping activities, thus enabling rapid work without the necessity of assuming difficult working positions. After the draping has been completed, the supporting stand for the cradle can be added, and the whole then released from the work support by releasing the securing structures and permitting member 14 to return to its normal dimensions, thereby freeing the completed article.

While the invention has been developed for the production of a specific article, and therefore presents characteristics which are specifically applicable to such article, the underlying features are such as will enable it to be used for the development of other articles of a somewhat similar type. And I therefore reserve the right to employ it in other relations, insofar as the same may fall within the spirit and scope of the invention as expressed in the accompanying claims.

What is claimed as new, is:

1. In the fabrication of articles requiring the draping of flexible material about an open-top handleless basket-like form with the form retained as a portion of the completed article, a work-support adapted to support the form in convenient position for developing the article including the drapery development, said support in-

cluding a member, means associated with at least one side and one end of said member and adapted to be adjusted laterally and longitudinally of said member to permit temporarily-anchored positioning within the form in the open-top zone of the latter, a rigid shaping template rising from said member and exposed above the top of the member and movable therewith, means for pivotally supporting the member in suspended position for swinging movement about a horizontal axis positioned in a plane above the member and its template, and means for pivotally supporting said member for swinging movement pivotally on a vertical axis extending through the member.

2. A support as in claim 1 wherein anvil elements are carried by the edge of said member.

3. A support as in claim 1 wherein the member is divided longitudinally to provide a pair of members one of which carries a dowel pin formation cooperative with the other portion to permit movements of the portions relative to each other in a single plane, said member having its portions spring-held and carrying a camming means operative to separate the portions for anchoring and releasing the member from the form.

4. A support as in claim 1 wherein the member carries an end-piece at one of its ends, said end-piece having a dowel-pin formation cooperative with the member to permit movement of the end-piece relative to the member in a single plane and to be secured in adjusted position, to thereby permit anchoring and releasing of the member relative to the form.

5. A support as in claim 1 wherein the member is divided longitudinally to provide a pair of members one of which carries a dowel-pin formation cooperative with the other portion to permit movements of the portions relative to each other in a single plane, said member having its portions spring-held and carrying a camming means operative to separate the portions for anchoring and releasing the member from the form, the division line of said member being positioned symmetrical to but spaced from the longitudinal axis of the member to provide portions of unequal width, said member also carrying an end-piece adjustably mounted at one end of the portion of greater width for completing the anchoring relationship.

6. A support as in claim 1 wherein the support means includes a vertical standard extending through the member, with the member and standard complementally formed to permit pivotal swinging of the member about the axis of the standard, and a supporting arm to which an upper zone of the standard is pivotally connected for bodily swinging of the standard and member about a horizontal axis.

LORA ALLEN MITCHELL.
